UNITED STATES PATENT OFFICE.

JOHN ATKINSON, OF MINNEDOSA, MANITOBA, CANADA.

DEVICE FOR MAKING AND CARRYING CIGARETTES.

Application filed February 3, 1923. Serial No. 616,727.

To all whom it may concern:

Be it known that I, JOHN ATKINSON, a subject of the King of Great Britain, residing at Minnedosa, in the Province of 5 Manitoba and Dominion of Canada, have invented certain new and useful Improvements in Devices for Making and Carrying Cigarettes, of which the following is a specification.

10 This invention has for its object the provision of a neat and attractive device which may be readily carried in the pocket of a garment and by the use of which cigarettes may be produced as needed. The invention 15 also seeks to provide a device which may contain a supply of rolled cigarettes as well as the papers or wrappers necessary for the production of the cigarettes. The invention also seeks to provide a device for the stated 20 purpose which will be compact, may be readily brought into position to permit the formation of cigarettes and which will facilitate renewal of the rolling apron when necessary. Other objects of the invention 25 will appear incidentally in the course of the following description, and the invention resides in certain novel features which will be particularly pointed out in the appended claims.

30 In the accompanying drawings:

Figure 1 is a perspective view of my device showing it closed in position to be carried in a garment pocket;

Fig. 2 is a longitudinal section on the line 35 2—2 of Fig. 1;

Fig. 3 is a transverse section on the lines 3—3 of Figs. 1 and 2;

Fig. 4 is a longitudinal section showing the device fully opened to permit the formation of a cigarette;

Fig. 5 is a detail longitudinal section through the cigarette-rolling mechanism showing the cigarette partly rolled, and

45 Figs. 6 and 7 are enlarged detail sectional views showing the manner in which the ends of the rolling apron are secured.

In carrying out my invention, I employ two cover members 1 and 2 which are similar in their external appearance and are hinged 50 together at one end, as shown at 3. The cover members have their ends and corner portions curved, as shown at 4, so as to have a neat appearance and avoid the formation of sharp corners which would tend to tear 55 the lining of a pocket. The hinge pin connecting the members 1 and 2 is carried by

the ends of side plates 5 which constitute the body or frame of the rolling mechanism and are joined at their ends remote from the hinge by a cross bar or frame member 6 60 which is curved so as to fit easily and closely within the cover members 1 and 2, as shown clearly in Fig. 2, and the said cross bar 6 and side bars 5 are formed externally with a longitudinal bead 7 against which the 65 edges of the cover members may abut. The edges of the cover members will preferably be slightly resilient so that they will fit snugly upon the member 6 and, therefore, be held in closed position frictionally so that, 70 while they will not be accidentally opened, they may be readily opened when access to the interior of the device is desired. By referring to Fig. 4 more particularly, it will be noted that the cover members 1 and 2 are 75 of a tray or dish-like form so that in closed position they will fit entirely around the frame consisting of the members 5 and 6. The cover member 2 is provided with a holding tray 8 which may be formed separately therefrom and secured therein by brazing or similar means or may be defined merely by the end members or flanges 9 formed upon the said cover member. It will be readily noted upon reference to Fig. 2 80 that this holder is adapted to contain a supply of cigarettes 10 so that, if the user prefers, a number of cigarettes may be made and carried in the cover for future use.

The cover member 1 is equipped upon its 90 interior with chambers or pockets 11 and 12 which are adapted to contain cigarette papers and matches, respectively, and are formed by a plate or partition 13 secured to and extending between the side portions of the cover member in spaced relation to the top thereof, and a partition 14 which extends between the plate 13 and the top of the cover member, as clearly shown in Fig. 3.

Extending longitudinally of the frame members 5 and secured to and between the same is a plate or table 15 upon which the cigarettes are rolled, and this table may be formed integral with the said side members, as will be readily understood upon reference to Fig. 3, or may be formed separately therefrom and intimately united therewith as may be preferred. One end of the said table or plate is disposed adjacent the hinge 100 3 and is carried downwardly and then forwardly to form an underlying re-entrant 110

flange 16 in which one end of the rolling apron 17 may be secured by a locking pin 18 forced into the flange 16 after the end of the apron has been placed therein in the 5 manner of a lining therefor, as clearly shown in Fig. 6. The diameter of the locking pin and the dimensions of the re-entrant flange should be such that, when the end of the apron is folded into the flange and the 10 locking pin then pressed into the fold of the apron, the end of the apron will be firmly bound within the flange. The opposite end of the plate or table 15 is spaced from the frame bar 6 and is formed into a 15 depending flange 19 so that a smooth surface will be presented to the apron 17 and cutting of the apron thereby prevented. The apron 17 is of such length that it will extend over the entire area of the table or 20 plate 15 and present a loose portion depending through the space at the forward end of the table to form a pocket 20, as shown most clearly in Fig. 4. The frame bar 6 has its upper edge extended inwardly and then forwardly to form an overhanging re-entrant flange 21 in which the end of the apron is received, as shown clearly in Fig. 7, and this end of the apron is secured in place by 25 a clamping bar 22, U-shaped in cross section and slightly resilient so that, if it be fitted over the fold or bight of the apron and the free edge of the flange 21, the end of the apron will be firmly gripped or clamped to the flange so that it is not apt 30 to be accidentally withdrawn. Immediately adjacent the flange 21, notches 23 are formed in the upper edges of the frame members 5 and mating notches 24 are formed in the edges of the cover member 1 so that a pin 25 35 may be received and held in the said notches. This pin 25 extends beyond the sides of the device slightly and is equipped at its ends with knobs or finger pieces 26 so that, when a cigarette is to be rolled, the pin may 40 be easily and conveniently held between the thumb and a finger of the user's hand. Mounted loosely upon the pin 25 is a roller 27 which, in the initial position shown in Fig. 4, will be disposed below the end of the 45 apron 17.

When a cigarette is to be made, the paper wrapper 28 therefor is placed in the bottom of the pocket 20 and the necessary tobacco is placed upon the paper, it being 50 readily noted that the paper will follow the outline of the pocket so that the tobacco will be confined within a space defined by the side edges of the paper. The knobs or finger pieces 26 are then lightly grasped by the 55 user and the pin 25 lifted from the notches 23 and pushed along the upper edges of the frame members 5. This manipulation of the pin 25 and the roller 27 carried thereby will 60 form a bight in the apron around the roller 65 so that a portion of the apron will extend

over the mouth of the pocket 20 and close the same. The apron and the wrapper 28 are thereby formed into a second bight enclosing the tobacco and initially forming the cigarette. As the roller 27 is caused to 70 travel toward the hinged end of the device, the apron will be put under tension and the cigarette caused to roll along the plate or table 15 in an obvious manner and compressed so that the paper wrapper will be 75 brought firmly around the tobacco and a neat finished cigarette produced. The table or plate 15 is of such length that, when the roller 27 has traveled the full length thereof, the cigarette will be fully made or rolled and 80 may then be smoked or may be placed in the holder 8 for future use.

From the foregoing description, taken in connection with the accompanying drawings, it will be seen that I have produced a 85 neat compact device whereby a smoker of cigarettes may readily produce his own cigarettes and finish them as perfectly as though they were factory make. The rolling apron will preferably be of silk or some equally 90 durable easily rolled material and may be readily renewed when worn out or damaged through possible accident. To remove a worn out or damaged apron, it is necessary 95 merely to withdraw the clamping member 22 from its engagement with the end of the apron and the flange 21, whereupon the end of the apron may be easily grasped and rolled back over the plate 15. The free end 100 of the apron may be easily pushed through the space between the hinge of the device and the adjacent end of the table or plate 15, whereupon a slight pull upon the apron will release the locking pin 18. A reverse 105 operation will secure a new apron in place in a very short period of time.

Having thus described the invention, what is claimed as new is:

1. A device for the purpose set forth comprising a frame member provided at one end in its upper edges with notches, a fixed table carried by said frame member and spaced from the notched end of the same, an apron secured to the end of the table and extending over the same and secured to the 110 end of the frame member to form a pocket between the same and the adjacent end of the table, a pin normally seating in the notches in the frame member and adapted to travel along the said member, and a roller 115 loosely mounted on said pin to engage the apron whereby travel of the roller along the frame member will cause the pocket of the apron to roll along the apron and the table.

2. A device for the purpose set forth comprising a frame member, a table extending longitudinally thereof and having its forward end spaced from the forward end of the frame member, the rear end of the table 120 125 130

- being provided with an underlying re-entrant flange and the forward end of the frame member being provided with an over-hanging re-entrant flange, an apron extending over the table and having one end fitted in the re-entrant flange thereof and the opposite end engaged in the re-entrant flange on the frame member, the apron forming a pocket between the end of the frame member and the adjacent end of the table, a locking pin engaged in the re-entrant flange on the table to frictionally retain the end of the apron therein, a clamping member fitting over the re-entrant flange on the frame member and the end of the apron engaged therewith, and a roller mounted to travel along the frame member and form a bight in the apron and cause said bight to roll over the table.
- 20 3. A device for the purpose set forth comprising a frame member, a fixed table in said member having one end spaced from the corresponding end of the frame member, the opposite end of the table being provided with an underlying re-entrant flange, an apron extending over the table and having
- one end fitted in the re-entrant flange and its opposite end attached to the frame member, the apron forming a pocket in the space between the frame member and the end of the table, a locking pin engaged in the re-entrant flange on the table to frictionally retain the end of the apron therein, and means to close the pocket in the apron and shift the pocket along the apron and the table.
- 25 4. A device for the purpose set forth comprising a frame member, a fixed table in the frame member having one end spaced from the corresponding end of the frame member, an overhanging re-entrant flange on said end of the frame member, an apron secured to and extending over the table and having one end fitted over and into the re-entrant flange on the frame member, a U-shaped clamping member fitted over said flange and the end of the apron engaged therewith, the apron forming a pocket between the frame member and the table, and means for shifting the pocket along the apron and the table.

In testimony whereof I affix my signature.
JOHN ATKINSON. [L.S.]
